Filed Aug. 11, 1969, Ser. No. 18,620

Term of patent 14 years

Int. Cl. D22—99

U.S. Cl. D22—99

FIG. 1 is a rear perspective view of a vehicle floor mounted gun rack, showing my new design;

FIG. 2 is a front elevational view of the vehicle floor mounted gun rack on a reduced scale;

FIG. 3 is a side elevational view thereof;

FIG. 4 is a top plan view; and,

FIG. 5 is a fragmentary rear elevational view taken in the direction of the arrows 5-5 in FIG. 3.

The gun butt holder and fragmentary gun are shown in broken lines in FIGS. 2 and 3 for illustrative purposes only.

I claim:

The ornamental design for a vehicle floor mounted gun rack, as shown and described.
